D. F. FOX.
FUEL HEATING DEVICE FOR EXPLOSIVE ENGINES.
APPLICATION FILED FEB. 20, 1915.

1,256,994.

Patented Feb. 19, 1918.

UNITED STATES PATENT OFFICE.

DENNIS F. FOX, OF CANDOR, NORTH CAROLINA.

FUEL-HEATING DEVICE FOR EXPLOSIVE-ENGINES.

1,256,994.

Specification of Letters Patent. Patented Feb. 19, 1918.

Application filed February 20, 1915. Serial No. 9,682.

To all whom it may concern:

Be it known that I, DENNIS F. FOX, a citizen of the United States of America, residing at Candor, in the county of Montgomery and State of North Carolina, have invented certain new and useful Improvements in Fuel-Heating Devices for Explosive-Engines, of which the following is a specification, reference being had therein

10 to the accompanying drawing.

This invention relates to a means for heating air to be applied or injected into a carbureter of an explosive engine, and has for its object the production of a simple and 15 efficient means whereby air may be taken into the carbureter from a point adjacent the exhaust, which exhaust is, while the engine is running, very hot.

Other objects and advantages of the present invention will appear throughout the following specifications and claim.

In the accompanying drawing:

Figure 1 is a side elevation of the explosive engine showing the heating device 25 applied thereto.

Fig. 2 is a perspective view of the heating device.

Fig. 3 is a central longitudinal section therethrough.

30 Fig. 4 is a transverse section through the heater showing the manner in which the same may be attached to the exhaust manifold of the engine, the exhaust manifold and portion of the explosive cylinder being 35 shown in dotted lines.

Fig. 5 is an enlarged longitudinal section of Fig. 3 taken on line 5—5, looking in the direction of the arrow.

By referring to the accompanying drawing it will be seen that 1 designates the explosive engine which is provided with the usual exhaust 2. An air inlet pipe 3 is clamped in engagement with the exhaust pipe 2 by means of clamps or other securing 45 means 4, and this pipe 3 is provided with an open end 5, and upon the lower face thereof is also provided with a plurality of air inlet apertures 6. It should be understood that this inlet pipe 3 is adapted to lie snugly against the exhaust manifold 2 as clearly illustrated in Figs. 1 and 4 so as to permit the air to be taken into the inlet pipe 3 as close as possible to the exterior of the pipe 2. It should be understood that the 55 inlet pipe 3 is not intended to take in the exhaust from the engine, but is adapted to

take in air adjacent the exhaust of the engine, which air is, of course, heated owing to the heated condition of the exhaust pipe. It should be understood that the pipe 60 3, as well as the entire heating device is formed of thin metal so as to permit the air passing therethrough to be readily heated by the radiation of the heat from the exhaust pipe 2 of the engine.

The inner end of the inlet pipe 3 is connected to an elbow 7, which elbow in turn engages a shank 8, which shank-pipe is slidably mounted within an auxiliary pipe 9, the pipe 9 being connected to a depending elbow 70 10. This elbow 10 engages one end of the telescoping pipe 11, and the opposite end of the pipe 11 engages the elbow 12. The telescoping pipe 11 is provided with a fresh air inlet aperture 13, which aperture is normally closed by a sleeve 14; the sleeve 14 is provided with a lug 14^a (Fig. 2) and an operating link 14^b is connected to said lug 14^a. The sleeve 14 is provided with an aperture 15 which is adapted to register 80 with the aperture 13 clearly shown in Fig. 5 to permit fresh air to be admitted into the pipe 11 and be discharged into the nozzle 16 when it is desired that fresh air be admitted into the carbureter 17. It should 85 be understood that the aperture 13 is of the same size as the discharge aperture 18 of the nozzle 16, so as to permit a uniform jet of air to pass from the aperture 13 out through the aperture 18. This nozzle is carried by the outer end of the elbow 12.

It should be understood that the pipes 8 and 9 telescope within each other and fit snugly together so as to permit the pipes to be adjusted to the different type of engines employed upon different make automobiles, and it should be understood that the pipe 11 is especially adapted to permit the adjustment of the pipe to the different 100 type of engines used upon the different make of automobiles, motor cars, and the like. It is, of course, obvious that some adjustable mechanism must be employed for the present device is adapted to be sold independently of the engine and is adapted 105 to be applied to any make or design of an engine used upon motor cars without departing from the spirit of the invention. It should be understood that the device may be made of any size and any material, 110 and other detail mechanical changes may be employed so long as the changes fall

within the scope of the claims without departing from the spirit of the invention. It should be understood that the nozzle 16 tapers toward its discharge end so as to fit 5 snugly and conveniently within the air inlet port 19 of the carbureter 17. It is desired to lay emphasis upon the fact that the present device is especially adapted to be used upon different species of engines, and 10 that owing to the adjustable feature thereof the same may be readily applied to the exhaust pipe of an engine and connected to the carbureter for conveniently feeding hot or warm air to the carbureter, and it should 15 be understood that when so desired, fresh air may be admitted to the carbureter by merely permitting the passage of air through the aperture 13 by bringing the apertures 13 and 15 into such a position as 20 to permit the same to register. The air, of course, will be drawn through the nearest point of communication with the outside atmosphere.

Having thus described the invention what 25 is claimed as new, is:—

In an apparatus of the class described, the combination of an inlet pipe provided with a plurality of aligned apertures formed in one side thereof, said inlet pipe provided

at one end with an elbow and being open 30 at its opposite end, a reduced shank-pipe inserted into one end of said elbow, an auxiliary pipe carried by said reduced shank-pipe, said auxiliary pipe provided with a vertically positioned elbow, said elbow provided with a two-section telescoping pipe, the lower section of said telescoping pipe being provided with an aperture and with an elbow, the apertured section of the telescoping pipe being slidably mounted within 40 the upper portion of said telescoping pipe, a sleeve rotatably mounted upon the lower section of the telescoping pipe between the elbow and the upper section of said pipe, said sleeve provided with an aperture adapted 45 to register with the aperture in the lower section of the telescoping pipe, said sleeve provided with a horizontal lug, an operating link pivotally mounted in said lug, and a reduced nozzle carried by said last-mentioned elbow. 50

In testimony whereof I hereunto affix my signature in presence of two witnesses.

DENNIS F. FOX.
